CLAIM

The ornamental design for a solid state directional lamp, as shown and described.

DESCRIPTION

The present application is related to U.S. patent application Ser. No. 13,167,351 (still pending), filed Jun. 23, 2011, and titled “Retroreflective, Multi-Element Design for a Solid State Directional Lamp”; U.S. patent application No. 13,167,394 (still pending), filed Jun. 23, 2011, and titled “Solid State Directional Lamp Including a Retroreflective, Multi-Element Directional Lamp Optic”; U.S. patent application No. 13,167,387 (still pending), filed Jun. 23, 2011, and titled “Hybrid Solid State Emitter Printed Circuit Board for Use in a Solid State Directional Lamp”; and U.S. patent application Ser. No. 13,167,410 (still pending), filed Jun. 23, 2011, and titled “Solid State Retroreflective Directional Lamp,” the entirety of each of which are hereby incorporated by reference.

FIG. 1 is a front perspective view of a solid state directional lamp showing my new design;

FIG. 2 is a front view of the solid state directional lamp of FIG. 1;

FIG. 2 is a side view of the solid state directional lamp of FIG. 1;

FIG. 3 is a top view of the solid state directional lamp of FIG. 1;

FIG. 4 is a bottom view of the solid state directional lamp of FIG. 1;

FIG. 6 is a rear view of the solid state directional lamp of FIG. 1; and,

FIG. 7 is a rear perspective view of the solid state directional lamp of FIG. 1.

The ornamental design which is claimed is shown in solid lines in the drawings. Any broken or phantom lines in the drawings form no part of the claimed design.

1 Claim, 5 Drawing Sheets
